EXERCISING DEVICE

Henry O. Costello, Providence, R. I., assignor to
 The Mortimer Newman Co., New Haven, Conn.,
 a corporation of Connecticut

Application May 24, 1945, Serial No. 595,583

5 Claims. (Cl. 272—78)

My invention relates to exercising devices of that kind which comprises a punching bag.

Objects of my invention are to enable a person to exercise or to train by the same movements as occur in a boxing fight, the punching bag playing the role of the opponent's head or face, to provide means holding the punching bag permanently before the person's face at a suitable distance, and to attach these means to the body of the person whereby the proper position of the bag is independent from the person's leg movements.

Other objects are resilient means carrying the bag and carried by the person in such a way that the bag will swing resiliently under the impact of the person's fist, but has a fixed position relative to the person except those dislocations which are caused by these resilient oscillations, to provide the bag over the resilient means whereby the bag will not oscillate in a rising arc but rather in an arc descending from its position of equilibrium in a manner similar to the head of an opponent, and hold the bag in a manner preventing any unintentional contact between the bag and the exercising person.

Further objects are to hold the bag at a suitable level, preferably at the level of the face of the exercising person, to hold the bag at a suitable distance from the person, and to provide for adjustment of this level and of this distance.

Still other objects are means connecting the holding device with the body of the exercising person, cords or similarly flexible means adapted to be wound around this body, these means being preferably affixed to points of the holding device which have different distances from the body of the person, and means connecting the holding device with two different levels of the person, for example with the shoulders and with the waist, whereby the holding device is reliably secured in its correct position.

Still further objects are to provide for simple, reliable and quick attachment of the exercising device to a person, for easy disconnection, and for simple and inexpensive manufacture of the device. Still other objects and advantages will appear from the following description of an exemplifying embodiment of my invention, from the appended claims, and from the accompanying drawing in which:

Fig. 1 shows a side view of an illustrative embodiment of my invention, attached to a person.

Fig. 2 shows the same embodiment in unattached condition seen from the right side in Fig. 1, the front part of the device being cut off along

the line 2—2 in Fig. 1 and the cords being represented in vertically spread positions.

Fig. 3 shows the same embodiment in the condition shown in Fig. 2, seen from the lower side.

Fig. 4 shows the front part of the same embodiment on a larger scale, seen in the same direction and condition as in Fig. 1, some parts being represented in cross-section taken along the line 4—4 in Fig. 3.

10 Referring to the drawing, numeral 1 indicates a plate or board consisting of a longish part 3 and two arms 5 extending from one end of the part 3 in symmetrically angularly spread directions whereby the arms 5 form a fork including a recess 6 and adapted to be placed in horizontal position around the front of a person's waist. The part 3 has a plurality of vertical bores or openings 7 positioned at different distances from the forked end of the plate 1. A threaded bolt 8 is inserted in one of the openings 7 and is secured to the arm 3 by an upper nut 9 and a lower nut 10. The bolt 8 can be adjusted vertically by turning the nuts 9 and 10 on the bolt, and can be adjusted horizontally by moving the bolt from one opening 7 to another.

25 A disk 11 is affixed to the upper end of the bolt 8. A similar disk 12 forms the lower end of a rod or shaft 13 and is connected to the disk 11 by resilient means, for example by a spiral spring 14. A punching bag or ball 15 inflated in usual manner is affixed to the upper end of the rod 13. Obviously adjustment of the bolt 8 also adjusts the position of the bag 15.

30 A supporting member, preferably a cord, string or band 16 has two ends affixed to the part 3 in any suitable manner. For example, these ends pass from above through vertical openings of the part 3 and are provided with knots 17 at the lower side.

35 40 A cord or similar supporting member 18 has one end affixed to one of the arms 5, for example, by passing this end from above through a vertical opening of this arm and knotting this end at 19. From the affixed end, the cord 18 may 45 run over an edge of this arm and may form a depending loop as shown in Fig. 2. Then, the cord 18 passes through another opening of the same arm 5 and terminates in an end 20 which is free in the condition shown in Fig. 2.

45 50 A similar cord 21 is arranged symmetrically to the cord 18 and is affixed to and passed through the other arm 5 correspondingly. The cord 21 has a free end 22.

55 A piece of cloth 23 may be affixed to the innermost surface of the recess 6 and may depend

from the surface. The piece 23 serves to cover the private parts of a person exercising in naked condition.

In some cases, for example if the exercising person is a child, this person may sit on the forked end of the plate 1 with his legs positioned at both sides of the part 3. In this position, the arms 5 form a broad part of the plate 1 secured to the person's body by the weight of this body, and it is not necessary to make use of the cords 18 and 21. The cord 16 may be used, if desired, as an additional support connecting the plate 1 with a higher level of the body.

Preferably, however, the device is attached to the exercising person in the manner illustrated by Fig. 1. In order to attach the device in this way, the person, facing the bag 15, steps with his right leg through the loop formed by the cord 18 and with his left leg through the corresponding loop of the cord 21. The free end of the cord 18 is wound around the back of the waist and runs at the other side which is not visible in Fig. 1 as far as the front of the body. The free end 22 of the cord 21 is wound around the back in opposite direction and meets the end 20 of the other cord at the front of the body. Here, the meeting ends 20 and 22 are connected, for example, by knotting the same. The loop formed by the cord 16 is placed over the shoulders around the neck of the person. The length of this latter cord is so adjusted that the cord 16 holds the plate 1 in a substantially horizontal position.

The punching bag 15 is so adjusted by the means described before that the bag can be hit or boxed by the person when the same uses his arms and fists in the manner of a boxer. For example, the upper part of the bag 15 is adjusted to the level of the boxer's nose and within reach of his fists, but sufficiently far from his body to avoid any contact of his face with the bag when the bag oscillates on the spring 14.

During the boxing exercise, the person may step or jump in the same manner as a boxer following or avoiding the movements of an opponent, and this person will find the punching bag always in a position suitable for striking, and corresponding to the position of the head or face of a supposed opponent whereby the person can exercise all parts of his body in the same manner as in a boxing fight, and the exercise constitutes a perfect training for such a fight.

I desire it understood that my invention is not confined to the particular embodiment shown and described, the same being merely illustrative, and that the invention may be carried out in

other ways without departing from the spirit of my invention as it is obvious that the particular embodiment shown and described is only one of the many that may be employed to attain the objects of my invention.

Having described the nature of my invention, what I claim and desire to secure by Letters Patent is:

1. An exercising device comprising a plate having a longish narrower part and a broader part affixed to one end of said longish part, said part forming a seat for a human body a resilient member having one end stiffly affixed to said longish part, and a punching bag affixed to the other end of said member.

2. An exercising device comprising a plate having two arms forming a forked end of said plate, said plate arms being adapted for two optional uses, one where the arms are placed at the waist of a human body and one where they serve as a seat for a human body a resilient member supported by the other end of said plate, and a punching bag supported by said member.

3. An exercising device comprising a plate having an end contacting a human body, means to hold said plate in horizontal direction on said body, a punching bag resiliently connected to said plate and positioned at a larger distance from said body contacting end than the largest distance of said bag from its position of equilibrium, and means to adjust said distance from said body contacting end.

4. An exercising device comprising a plate having two arms forming a forked end of said plate, said plate arms being adapted for two optional uses, one where the arms are placed at the waist of a human body and one where they serve as a seat for a human body, a resilient member supported by the other end of said plate, a punching bag supported by said member, and means to adjust the horizontal distance of said member from said forked end.

5. An exercising device comprising a plate having two arms forming a forked end of said plate, said plate arms being adapted for two optional uses, one where the arms are placed at the waist of a human body and one where they serve as a seat for a human body, a resilient member supported by the other end of said plate, a punching bag supported by said member, means to adjust the horizontal distance of said member from said forked end, and means to adjust the vertical distance of said punching bag from said plate.

HENRY O. COSTELLO.
